(57) **CLAIM**

I claim the ornamental design for a light emitting diode module, as shown and described.

DESCRIPTION

FIG. 1 is a top plan view of a light emitting diode module according to a first embodiment of my new design;

FIG. 2 is a front view of the light emitting diode module;

FIG. 3 is a bottom view of the light emitting diode module;

FIG. 4 is a rear view of the light emitting diode module;

FIG. 5 is a left side view of the light emitting diode module;

FIG. 6 is a right side view of the light emitting diode module;

FIG. 7 is a sectional view of the light emitting diode module taken along lines 7—7 in FIG. 1;

FIG. 8 is a top plan view of a light emitting diode module according to a second embodiment of my new design;

FIG. 9 is a front view showing the light emitting diode module of the second embodiment;

FIG. 10 is a bottom view showing the light emitting diode module of the second embodiment;

FIG. 11 is a rear view showing the light emitting diode module of the second embodiment;

FIG. 12 is a left side view showing the light emitting diode module of the second embodiment;

FIG. 13 is a right side view showing the light emitting diode module of the second embodiment; and,

FIG. 14 is a sectional view of the light emitting diode module taken along lines 14—14 in FIG. 8.
